UNITED STATES PATENT OFFICE.

EARL G. WATROUS, OF CHICAGO, ILLINOIS.

DESIGN FOR A LIQUID-SOAP PUMP.

• **57,175.**

Specification for Design.

Patented Feb. 22, 1921.

Application filed November 17, 1919. Serial No. 338,770. Term of patent 14 years.

To all whom it may concern:

Be it known that I, EARL G. WATROUS, a citizen of the United States, residing at Chicago, in the county of Cook and State of Illinois, have invented a new, original, and ornamental Design for a Liquid-Soap Pump, of which the following is a specification, reference being had to the accompanying drawing, forming part thereof.

The figure shown in this drawing is a perspective view of a liquid soap pump showing my new design.

I claim:

The ornamental design for a liquid soap pump as shown.

EARL G. WATROUS.
